COMBINED TELEVISION RECEIVER AND SUPPORT STAND THEREFOR

Reid S. Larsen, 4436 Illinois Ave., Fair Oaks, Calif.
95628, and Charles Allen Elggren, 1211 Walker Bank
Bldg., Salt Lake City, Utah 84111

Filed Apr. 15, 1969, Ser. No. 16,750

Term of patent 14 years

Int. Cl. D14—03

U.S. Cl. D56—4

FIG. 1 is a side perspective view of our new design for a self-contained T.V. entertainment device;

FIG. 2 is a reduced side elevational view thereof partially broken away;

FIG. 3 is a top plan view thereof partially broken away; and

FIG. 4 is a reduced end elevational view thereof as viewed from the left in FIG. 1.

The side not shown is a mirror image of the side shown in FIG. 2.

We claim:

The ornamental design for a combined television receiver and support stand therefor, substantially as shown and described.
